UNITED STATES PATENT OFFICE.

LOUIS SCHRAM AND DOMINIQUE KIES, OF CHICAGO, ILLINOIS; SAID KIES, ASSIGNOR TO SAID SCHRAM.

MUSIC-CABINET.

No. 838 017.

Specification of Letters Patent.

Patented April 28, 1908.

Application filed March 7, 1908. Serial No. 419,747.

To all whom it may concern:

Be it known that we, LOUIS SCHRAM and DOMINIQUE KIES, citizens of the United States, residing at 20 Armour street, Chicago, 5 in the county of Cook and State of Illinois, have invented a new and useful Improvement in Music-Cabinets, of which the following is a specification.

Our invention relates to improvements in 10 cabinets for holding music, drawings and the like articles, in sheet form or phonograph disk records, and the like; and our object is to provide such a cabinet of a novel and improved construction rendering it particularly desirable for its purpose.

In the accompanying drawing we illustrate, by a vertical sectional view, a music cabinet constructed with our improvements showing two receptacles respectively in 20 closed and opened position.

The compartments 1 and 2 of the cabinet are each provided with a door 3 suitably hinged at its lower end, as by the pivot pins 4. 5, 5 are receptacles for sheets of music, 25 and the like, each formed of a series of compartments 6, separated from each other by partitions or slides, 7. Each receptacle 5 is connected at the top of its forward side, by means of suitable hinges 8, with the top portion of the respective door 3; and each receptacle is also pivotally connected at about the points 9, at opposite ends, with the upper ends of swinging links 10, which at their lower ends are pivoted at 11 to the inner sides 35 of the cabinet.

When the door 3 is closed, the receptacle 5 rests at its rear end upon a stop 12 and hangs at its forward end from the pivots 8. As the door is opened the top of the receptacle 40 moves with the upper part of the door and the body of the receptacle swings upon the links 10 until the forward face of the receptacle contacts with the rear face of the door. The link connection prevents further movement 45 of the parts and permits the door to be opened just far enough to expose the open tops of all the compartments 6. When the sheets of music, or the like, are placed in a compartment 6, they rest against the forward wall of the compartment, and the backward movement of the lower part of the receptacle, as the door is closed, keeps the receptacle always in an inclined position which prevents the sheets from falling over or curl-

ing or sagging, as would be apt to be the case 5 if the compartments assumed a vertical position when the door is closed. To permit the swinging of the receptacle in and out of the cabinet as described, it is necessary that the top of the receptacle shall incline in the 60 backward direction. It is undesirable, however, to have the base of the receptacle incline in a manner to form an obtuse angle to the partitions 7 of the receptacle, because this would tend to cause the sheets to slide backward at their lower edges and produce curling or bending of the sheets. In order that the rear compartments of the receptacles may be of desired depth and the bases of the compartments at right-angles to the walls there- 70 of, we provide the said bases at different elevations in the form of steps as indicated.

The swinging connections of the receptacle are such that when the door is swung outward about half way, it will drop normally to 75 its opened position and when swung upward about, or a little over half way, it will move normally to its closed position, the receptacle operating as a lock to hold the door and attendant parts either opened or closed.

The receptacle 5 may be arranged to hold phonograph disk records by, as is usual, having the compartments extend from front to back, that is to say at a right angle to the compartments 6 shown.

While we prefer to construct our improvements throughout as described, they may of course be variously modified in their details without departing from the spirit of our invention as defined by the claims.

What we consider new and desire to secure by Letters Patent, is—

1. In a cabinet of the character described, the combination of a door hinged to swing from its lower end-portion, a receptacle in the 95 cabinet connected with the door to move coincidently therewith at its upper end, and means for swinging the receptacle at its lower end toward and away from the door in the movements of the latter, for the purpose 100 set forth.

2. In a cabinet, of the character described, the combination of a door hinged to swing from its lower end-portion, a receptacle in the cabinet connected with the door to move 105 coincidently therewith at its upper end and swinging link-supports for the receptacle operating to swing the lower end of the recep-

tacle toward and away from the door in the movements of the latter, for the purpose set forth.

3. In a cabinet, of the character described, 5 the combination of a door hinged to swing from its lower end-portion, a receptacle in the cabinet connected with the door to move coincidently therewith at its upper end and swinging means for the lower end of the receptacle operating to move said lower end away from the door in the closing movement thereof and to said door in its opening movement to limit the same, substantially as and for the purpose set forth.

15 4. In a cabinet of the character described, the combination of a door hinged to swing

from its lower end-portion a receptacle in the cabinet having a series of partitions separating it into compartments and bottoms for the separate compartments at different elevations and extending at right-angles to the partitions, said receptacle being connected with the door to move coincidently therewith at its upper end, and means for swinging the receptacle at its lower end toward and away from the door in the movements of the latter, substantially as set forth. 20 25

LOUIS SCHRAM.
DOMINIQUE KIES.
